(57) **CLAIM**

The ornamental design for a motor vehicle front lower bumper, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a motor vehicle front lower bumper showing our new design;

FIG. 2 is a rear perspective view thereof;

FIG. 3 is a front view thereof;

FIG. 4 is a rear view thereof;

FIG. 5 is a right side view thereof, the left side view being a mirror image;

FIG. 6 is top view thereof; and,

FIG. 7 is a bottom view thereof.
